GRINDING MACHINE

John Heward Twombly, Hill, N. H.; Florence D. Twombly executrix of said John Howard Twombly, deceased

Application March 23, 1951, Serial No. 217,269

4 Claims. (Cl. 51—79)

1

This invention relates to grinding machines and more particularly to machines for performing the operation of reducing the diameter of wires or rods. Such machines are used in the production of needles and the like, and also for "necking" or reducing the diameter through an intermediate portion of the length of rods or wires, for example tone rods for toy pianos.

A general object of the invention is the provision of a simple, relatively inexpensive, and highly efficient machine for performing a necking operation or a similar grinding operation upon wires or rods of varying diameters.

More specifically, it is an object of the invention to provide a grinding machine of the type described, comprising a base, a grinding wheel rotatably supported above said base, a plurality of threaded rollers rotatably supported beneath said grinding wheel for successively advancing a plurality of rods or wires to and beneath the grinding wheel, and means for rotating the grinding wheel and the threaded rolls. Another object is the provision, in a grinding machine of the type described, of an adjustable support for the grinding wheel such that the latter may be adjusted vertically toward and away from the base, and may also be tilted about an axis parallel to the base and perpendicular to the grinding wheel axis, so as to insure equal grinding action at either end of the wheel or, alternatively, to adjust the wheel so as to grind points of any desired length at the ends of the rods or wires.

Another object is the provision, in a machine of the character described, of a backboard or guard member arranged parallel and adjacent to the threaded rolls for advancing the rods or wires, the backboard or guard member serving the purpose of preventing the wires or rods from advancing along their own axes during their progress along the threaded rolls, until after they have been subjected to the grinding operation.

A further object is the provision, in a machine of the character described, of means supported adjacent the grinding wheel for frictionally engaging the wires and rods as they are successively presented to the grinding wheel and causing them to rotate about their own axes as they are advanced by the threaded rolls.

Other and further objects, features and advantages will be apparent from the description which follows, read in connection with the accompanying drawings in which

Figure 1 is a front elevation of a machine constructed in accordance with the present invention;

Figure 2 is a plan view of the machine illustrated in Figure 1;

Figure 3 is an end elevation of the machine illustrated in Figures 1 and 2;

Figure 4 is a vertical section on line 4—4 of Figure 2;

2

Figure 5 is a vertical section on line 5—5 of Figure 2;

Figure 6 is a vertical section on line 6—6 of Figure 2;

5 Figure 7 is a vertical section on line 7—7 of Figure 3;

Figure 8 is a horizontal section on line 8—8 of Figure 1;

10 Figure 9 is a rear perspective view of the upper portion of the machine;

Figure 10 is an enlarged fragmentary sectional view showing the engagement of the rods being processed with one of the threaded rolls for advancing them, and with the frictional member for inducing their rotation about their own axes; and

15 Figure 11 is an elevational view of a tone rod for a toy piano, after passing through the machine.

20 In order to facilitate an understanding of the invention, reference is made to the embodiment thereof shown in the accompanying drawings and detailed descriptive language is employed. It will nevertheless be understood that no limitation of the invention is thereby intended and that various changes and alterations are contemplated such as would ordinarily occur to one skilled in the art to which the invention relates.

25 Referring particularly to Figures 1 and 2, a machine constructed according to the invention comprises generally a base 10 to which is secured a horizontal support 11 and a vertical support 12, the latter being secured to the base 10 by means of bolts 13 extending through slots 14 in the base 10 so that the support 12 is adjustable thereon. The horizontal support 11 is provided at its respective ends with the two upstanding end portions 15 in which are journaled a plurality of helically threaded rolls 16, 17 and 18. As best seen in Figure 4, the said rolls are provided at one end with toothed pinions 19, 20 and 21, respectively, meshing with intermediate idlers 22 and 23, the pinion 20 being fast upon the shaft 24 of roll 17, which shaft also carries a pulley 25. Means are thus provided for rotating the several rolls in unison. Each of the rolls is provided with a helical thread of the same pitch as the others, whereby a rod or length of wire laid across the rolls at right angles will be advanced translationally, that is to say 30 without alteration of its right angle relation to the rolls.

35 The rotation of the rolls 16—18 in the illustrated embodiment is clockwise looking from the right-hand end of the machine, which will tend 40 to advance the rods 26 (Figure 2) to the right and would also tend to advance them rearwardly of the machine, in the direction of their own length. To prevent this latter movement a backboard or guard 27 is secured along the rearward edge of 45 the support 11, the guard 27 terminating at a point 28 which is short of the right-hand end of 50

the support 11. After the rods have been operated upon by the grinding wheel, and have passed the end 28 of the guard 27, they are permitted to move rearwardly of the machine until they are overbalanced by their own weight and fall off of the threaded rolls into a suitable receptacle.

The vertical support 12 is provided with a dovetailed recess as at 30 and a vertically adjustable member 31 is slidably mounted within said recess through the medium of bolts 32 extending through slots 33 in the support 12 (Figure 9). Adjustment of the member 31 relative to the support 12 is obtained through the medium of adjusting screws 34, 35 (Figure 7), the screw 34 having threaded engagement with the rearwardly extending horizontal top portion 36 of the member 31 and having a thrust engagement with the top surface of the support 12. The screw 35 is freely rotatable in the top portion 36 of member 31, and has threaded engagement with the support 12. The screws 34 and 35 thus effect, respectively, a push-and-pull relationship between the member 31 and the support 12, for vertical adjustment of the member 31, which may then be firmly secured in the adjusted relationship by tightening of the bolts 32.

A third vertical member 37 is mounted on the vertically adjustable member 31 by means of a bolt 38 threaded into the member 37 and freely rotatable in member 31, so that member 37 is tiltable in a vertical plane about the axis provided by the bolt 38. Adjustment of the tilting member 37 is secured by means of screws 39 and 40 having threaded engagement with the horizontally projecting flange 41 of the member 31 and bearing upon the upper edge of the tilting member 37. The latter may be secured in adjusted relationship by tightening the bolt 38 against collar 42 which in turn bears on member 31 (Figure 6).

The tilting member 37 carries horizontally extending arms 43 at its respective ends, said arms being formed to provide bearings 44 for the shaft 45 of a grinding wheel 46. A driving pulley 47 is secured on one end of the shaft 45. On the outer ends of the respective arms 43, beyond the bearings 44, are secured short extensions 48 for supporting, through bolts 49, a presser foot or friction member 50, the vertical relationship of the respective ends of the latter being adjustable by means of nuts 51, 52 on the bolts 49. The friction member 50 is so adjusted as to engage the upper surfaces of the rods or wires 26 as they are successively presented to the grinding wheel 46 and by reason of the friction between the member 50 and the rods, to cause the latter to rotate about their own axes as they are advanced by the threaded rolls, thus causing the rods to be ground uniformly about their axes.

From the foregoing description it is believed that the operation of the machine will be understood without difficulty.

A succession of rods or wires to be operated upon is placed upon the rolls 16-18 at the left-hand end of the machine and by rotation of the rolls, will be advanced toward the right. As they successively pass beneath the friction member 50 they are engaged by the latter and caused to rotate about their respective axes, meanwhile being engaged by the grinding wheel 46 rotating about its own axis at right angles to the rods. As the rods are advanced past the grinding wheel they are ground uniformly about their axes and,

as they are advanced further, past the end 28 of the backboard or guard 27, they are advanced rearwardly of the machine and dropped therefrom. By reason of the described relationships, 5 the grinding wheel is vertically adjustable with the sliding member 31, and its axis may be tilted in a vertical plane, as desired, by tilting adjustment of the member 37 relative to the member 31.

The machine is adapted to the rapid and efficient performance of the described operations, 10 and has a much greater capacity than other known machines for performing similar operations.

Having thus described the invention, what is 15 claimed as new and desired to be obtained by Letters Patent is:

1. Rod grinding machine comprising a base, a vertical support secured on said base, a grinding wheel rotatably mounted on said support, a 20 plurality of helically threaded parallel rolls rotatably supported below said grinding wheel and adjacent thereto, for advancing a succession of rods, disposed crosswise thereof, to and beneath said grinding wheel, a stationary friction member supported adjacent said wheel and said rolls for engaging rods advanced by said rolls and causing the same to rotate about their axes while passing beneath said wheel, means for rotating said wheel, and means for rotating said rolls.
2. Rod grinding machine comprising a base, a vertical support secured on said base, a grinding wheel rotatably mounted on said support, a 25 plurality of helically threaded parallel rolls rotatably supported below said grinding wheel and adjacent thereto, for advancing a succession of rods, disposed crosswise thereof, to and beneath said grinding wheel, means for rotating said wheel, and means for rotating said rolls, said vertical support comprising a guideway member secured on said base, a vertically adjustable member mounted on said guideway member, and a third member mounted on said vertically adjustable member, said third member including 30 bearings for said grinding wheel.
3. Rod grinding machine as defined in claim 2, said third member being tiltable about an axis lying parallel to said base and at right angles to the axis of said bearings.
4. In a rod grinding machine, in combination, 35 a plurality of helically threaded parallel rolls, a grinding wheel mounted to rotate above said rolls on an axis generally parallel to the axes of said rolls, means to rotate said rolls and said wheel, and means for causing rods advanced by said rolls to rotate about their axes while passing beneath said wheel, said last means comprising a stationary member supported adjacent said wheel in position to engage frictionally said rods.

JOHN HOWARD TWOMBLY.
